(57) **CLAIM**

The ornamental design for a reversible pet harness, as shown and described.

DESCRIPTION

FIG. 1 is a front perspective view of a reversible pet harness showing our new design in a condition of use in a first configuration and with a ring extending from a first side of the reversible pet harness;

FIG. 2 is a front perspective view thereof;

FIG. 3 is a rear perspective view thereof;

FIG. 4 is a front elevational view thereof;

FIG. 5 is a rear elevational view thereof;

FIG. 6 is a right-side elevational view thereof;

FIG. 7 is a left-side elevational view thereof;

FIG. 8 is a top plan view thereof;

FIG. 9 is a bottom plan view thereof;

FIG. 10 is an enlarged front perspective view thereof;

FIG. 11 is an enlarged rear perspective view thereof;

FIG. 12 is a front perspective view of the reversible pet harness of FIG. 1 shown in a condition of use in a second configuration inverted from the first configuration with the ring moved to extend from a second side of the reversible pet harness;

FIG. 13 is a front perspective view thereof;

FIG. 14 is a rear perspective view thereof;

FIG. 15 is a front elevational view thereof;

FIG. 16 is a rear elevational view thereof;

FIG. 17 is a right-side elevational view thereof;

FIG. 18 is a left-side elevational view thereof;

FIG. 19 is a top plan view thereof;

FIG. 20 is a bottom plan view thereof;

FIG. 21 is an enlarged front perspective view thereof; and,

FIG. 22 is an enlarged rear perspective view thereof.

The longer equally spaced broken lines on the reversible pet harness depict portions of the reversible pet harness that form no part of the claimed design. The shorter equally spaced broken lines on the reversible pet harness depict stitching that forms no part of the claimed design. In FIGS. 1 and 12, the longer equally spaced broken lines showing a
